Henry Whitney's Design for an Inkstand

4292

PATENTED AUG 9 1870

Inventor
Henry Whitney

Witnessed,
S. E. Batchelder
W. Cambridge

United States Patent Office.

HENRY WHITNEY, OF EAST CAMBRIDGE, MASSACHUSETTS.

Design No. 4,292, dated August 9, 1870.

DESIGN FOR AN INKSTAND.

The Schedule referred to in these Letters Patent and making part of the same.

To all whom it may concern:

Be it known that I, HENRY WHITNEY, of East Cambridge, in the county of Middlesex and State of Massachusetts, have invented a Design for an Inkstand; and I hereby declare the following to be a full, clear, and exact description of the same, reference being had to the accompanying photographs, making part of this specification, in which are represented two perspective views of my new design for an inkstand.

The object of my invention is to produce an ornamental and unique design for an inkstand; and

My invention consists in a receptacle of a boat or ship form, provided with a cap, at which point the inkstand is supplied with ink.

In the accompanying photographs—

A represents a receptacle of the form of a minia-

ture boat or ship resting upon a pair of chocks, B, or other suitable support.

Access to the interior of the receptacle for supplying and using the ink is obtained through a hole, a, in the cap C, which is provided with a cover, D, hinged thereto at b.

Claim.

What I claim as my invention, and desire to secure by Letters Patent, is—

The design for an inkstand herein shown and described.

Witness my hand this 20th day of July, A. D. 1870, in presence of—

Witnesses:

N. W. STEARNS,
W. J. CAMBRIDGE.

HENRY WHITNEY.
